J. S. BAIN.
CORN DRIER SPUR.

APPLICATION FILED JAN. 6, 1919.

UNITED STATES PATENT OFFICE.

JOSEPH SMITH BAIN, OF CEDAR RAPIDS, IOWA.

CORN-DRIER SPUR.

1,322,394.

Specification of Letters Patent. Patented Nov. 18, 1919.

Application filed January 6, 1919. Serial No. 269,924.

To all whom it may concern:

Be it known that I, JOSEPH SMITH BAIN, a citizen of the United States, residing at Cedar Rapids, in the county of Linn and 5 State of Iowa, have invented certain new and useful Improvements in Corn-Drier Spurs; and I do hereby declare the following to be a full, clear, and exact description of the invention, such as will enable others 10 skilled in the art to which it appertains to make and use the same.

This invention relates to seed-corn drying devices, and more particularly to the drier illustrated and described in Letters Patent 15 No. 1,026,550, issued to Joseph Smith Bain and Benjamin L. Bain on the fourteenth day of May, 1912.

The object of this invention is to improve the construction of the ear-holding prong or 20 spur, so as to permit the use, especially in single spurs, of round wire, and that of an ordinary commercial quality. The improved spur also possesses advantages peculiar to its construction, which will be 25 more fully set out hereafter.

In the manufacture of seed-corn driers applicant has used the type of prong shown 30 in Figs. 3 and 4 of said patent, the one shown in Fig. 5 being not only difficult to form, but being wasteful of material, inasmuch as the double shank of the looped hook must be about twice as long as necessary, in order to permit hooking over the supporting bar. To secure the best results the prong 35 has been made of flat wire, which would hug the supporting bar snugly, and would not swing sidewise, as would a loop of round wire. This, however, called for special wire, not on the general market, and of a temper 40 stiff enough, flatwise, to support the corn without collapsing. By reason of this hard temper it has been impossible to make a short enough bend at the loop, without cracking the wire, so that supporting bars 45 as thin as desired could be used. These objections and disadvantages are entirely removed in the improved prong, which will now be described.

In the accompanying drawing, Figure 1 50 is a view in perspective showing my improved prong or spur, both single and double, in position on a piece of supporting bar. Fig. 2 is a plan view showing one of them as seen from the under side.

55 The supporting bar is preferably of rather thin steel, approximately $\frac{1}{8}$ " thick

by about one inch in width. This bar 1 is supposed to be attached to a suitable frame, round, rectangular, or otherwise, as desired. It stands vertically edgewise, as indicated, 60 and requires no machining, except the drilling or punching of holes for attachment to the frame. Along it are set the prongs 2, or 3, which pinch it tightly enough to keep their proper position. In Fig. 1 the first 65 prong at the left is a single one, as seen from the back side. The second is the same, as seen from the front side. The third is a double prong, 3.

Referring to the single prong 2, its 70 pointed tang 2^a is supposed to penetrate the butt end of the corn-cob, as indicated by the outlined ear of corn. At 2^b is a bend, of somewhat less than a right angle, so that the tang inclines upwardly to hold the ear. 75 A short distance from this bend is a return-bend or loop 2^c, which should be short enough to barely admit the bar 1 edgewise. That portion of the wire opposite the stem 2^d of the loop is formed as an eye 2^e, the 80 stem 2^d crossing it practically in the middle. The eye lies closely enough to the stem so that the bar is pinched snugly by them when the spur is placed in position. This gives the spur a broad, three-point bearing on the 85 bar, and holds it securely against slipping, turning, or bending sidewise.

It is to be noted that the form of the spur is such that the pushing of the ear on the tang tends rather to tighten than loosen the 90 pinch of the spur on the bar.

By bending the wire at 3^b and extending it as a tang 3^a, a double-pointed spur is formed with the minimum of labor or material. All the advantages incident to the 95 single spur apply equally to the double one.

The construction admits of the use of a comparatively soft wire, easily bent to the form of the close loop shown. The material is not only lighter in proportion to its supporting stiffness, as compared with the flat wire spur, but permits the use of much lighter stock for the supporting bars. The round wire tang is also more easily inserted in the corn-cob, though this is of secondary 100 importance.

Having thus described my invention, I claim:

1. A spur for corn-driers, comprising a tang to pierce the corn-cob, a loop formed 110 of a part of the material of which the tang is composed and a stem uniting the loop and

tang, the stem being bent to cross the loop centrally and at a little distance therefrom, whereby the spur may be attached to a supporting bar by a three-point pinching contact.

2. A spur for corn-driers, comprising a pair of terminal tangs, an intervening loop formed of the same material as the tangs, and a stem uniting the loop with one of the tangs, the stem being bent to cross the loop

centrally, whereby the oppositely projecting tangs are supported on a bar by a three-point pinching contact.

In testimony whereof I affix my signature in presence of two witnesses.

JOSEPH SMITH BAIN.
